UNITED STATES PATENT OFFICE

HORACE W. HALL, OF NEWTON, MASSACHUSETTS

APPARATUS FOR ROUTING

Application filed May 11, 1931. Serial No. 536,348.

This invention relates to an apparatus for routing, and more particularly to one for cutting channels in rackets intended to be strung.

In the manufacture of rackets it is the practice to cut channels in the upper portion of the bow head of a racket between certain string holes so that the strings will be slightly below the outer surface of the bow head, and thus not be exposed and subject to wear when that portion of the racket comes in contact with anything. These channels are commonly cut by a grinding wheel, consequently they are rough and of uneven width and depth, and it is necessary to break the corners down with a metal punch so they will be less likely to fray the strings; but even after all this work these channels are so crudely made that they have always been unsatisfactory.

One object of my invention is to provide routing apparatus which will cut these channels to an even width and depth and leave a smooth, plane surface. Another object has been to construct my apparatus so that the racket may readily be placed and held in working position, and so that the channeling may be quickly accomplished by simple operations.

The foregoing and other objects which will appear as the nature of the invention is better understood, may be accomplished by a construction, combination and operative arrangement of parts such as is disclosed by the drawings. The nature of the invention is such as to render it susceptible to various changes and modifications, and, therefore, I am not to be limited to the construction disclosed by the drawings; but am entitled to all such changes therefrom as fall within the scope of my claims.

In the drawings:

Figure 1 is a front elevation showing my jig and a racket in position ready to be channeled.

Figure 2 is a top plan view looking down on my routing jig, the racket being represented by dotted lines.

Figure 3 is a side elevation of my routing jig.

Figure 4 is a cross-section taken on the line

4—4 of Figure 1 showing the router guard in a slot in the jig and a cutting bit extending into a hole in the racket ready to cut a channel from there to the next hole.

Figure 5 is a front elevation showing my 55 jig and racket held in working position by spring means, said means being shown in end view.

Figure 6 is a front elevation of the spring 60 means fastened to the floor.

As illustrated, my device consists of a jig 65 or form 11 preferably made of metal or some other durable material, which is fastened to a table or bench 12 near the front thereof by screws 13. A section of said table at the front thereof is cut out as at 14, shown in Figure 2 of the drawings. Said jig extends over and above said cut-out portion 14. The shape of said jig is such that the upper portion of the head of a racket 16 contacts with 70 the inner surface thereof.

Said jig 11 is provided with guide blocks 75 17 on each side thereof, preferably opposite each other, which guides 17 extend downwardly. These blocks 17 are spaced apart on opposite sides slightly farther than the width or cross thickness of the wooden bow head of the racket which is between them, so that it may be moved slightly between said blocks in lining it up with slots 18 which are 80 cut in said jig 11 at certain points. These slots 18 are of such shape that channels 19 may be cut between holes 20 which are drilled through the bow head of the racket at certain points for stringing purposes. 85

A router 23 is used to cut the channels, it having a guard 24 at its lower end and a bit 25 projecting beyond said guard, the projecting distance determining the depth of the channels 19, their width being determined by the diameter of said bit. Said guard is of such a size that it fits into said slots 18 and may be moved therein, the slots, of course, being wider than the channels to be cut and extending slightly beyond the holes 20 so that said router 23 may be moved until the bit 25 reaches said holes; but not go beyond. 95

In order that the racket may automatically be held in working position in my jig I provide spring means composed of upper and 100

lower bow springs given the numerals 26 and 27 respectively, fastened or pinned together at their ends as at 28 and screwed to a floor 29. A foot lever 30 is fastened to said upper bow spring 26 and extends at approximately right angles thereto. A rest member 31 is also fastened to said upper bow spring 26, as shown in Figures 5 and 6 of the drawings, by the same bolts 32 which hold said foot lever 30. This rest member 31 preferably increases in thickness or is higher from the center towards the outside ends, and is shown in said Figure 5 as concaved. As the racket handle should rest on the center or lower portion of said rest member 31 the higher concaved surface tends to prevent it from moving sidewise.

My apparatus is operated by pressing the foot lever 30 downwardly thereby compressing said bow springs, until there is sufficient space between said jig 11 and said rest member 31 to insert a racket in position, then said lever is released and said bow springs expand forcing the racket against said jig 11 while still under tension and firmly holding it there in working position. Care must be exercised to see that the slots 18 are lined up with and overlie the racket holes 20 as illustrated in Figure 2 of the drawings. The router guard 24 is inserted into said slots 18 and the bit 25 extends into a hole 20 in the racket, whereupon the router is moved across from one hole to another as it is revolved at a very high speed, the slots 18 being sure guides, so that the cutting ceases when the guard 24 contacts with the end of a slot. I have found in practice that a rotating speed for the router of 18,000 R. P. M. does the channeling properly, making a smoothly finished surface.

What I claim is:

1. Router apparatus comprising a jig shaped to fit on the upper portion of a racket bow head, said jig having slots therein which extend between and slightly beyond holes drilled in said bow head portion in predetermined locations, and means adapted to automatically hold said racket against said jig.

2. Router apparatus comprising a jig shaped to fit on the upper portion of a racket bow head, said jig embodying guide members at opposite sides thereon, said jig having slots therein which extend between and slightly beyond holes drilled in said bow head portion in predetermined locations, and resilient means adapted to firmly hold said racket in working position in said jig between said guide members, said means being so positioned with relation to said jig that said means are under tension when said racket is in said working position.

3. Router apparatus comprising a jig shaped to fit on the upper portion of a racket bow head, said jig having slots therein which extend between and slightly beyond holes

drilled in said bow head portion in predetermined locations, and means adapted to automatically hold said racket against said jig, said means comprising bow springs fastened together. 70

4. Router apparatus comprising a jig shaped to fit on the upper portion of a racket bow head, said jig having slots therein which extend between and slightly beyond holes drilled in said bow head portion in predetermined locations, and means adapted to automatically hold said racket against said jig, 75 said means comprising an upper bow spring and a lower bow spring fastened together, and a rest member on said upper bow spring 80 on which the racket may rest.

5. Router apparatus comprising a jig shaped to fit on the upper portion of a racket bow head, said jig having slots therein which extend between and slightly beyond holes 85 drilled in said bow head portion in predetermined locations, and means adapted to automatically hold said racket in working position against said jig, said means embodying bow springs fastened together, a concave-shaped rest member on one of said bow springs for the racket to rest on. 90

6. Router apparatus comprising a jig shaped to fit on the upper portion of a racket bow head, said jig having slots therein which extend between and slightly beyond holes drilled in said bow head portion in predetermined locations, and spring means adapted to automatically hold said racket against said 95 jig embodying a lever which is adapted when operated to compress said spring means.

7. Router apparatus comprising a jig shaped to conform to the upper outside portion of a racket bow head, a table to which said jig is fastened, said table having a portion, 105 cut out at the front thereof, said jig being fastened to said table at points just beyond said cut-out portion, said jig extending above and over said cut-out portion.

8. Router apparatus comprising a jig 110 shaped to conform to the upper outside portion of a racket bow head and having slots therein, a table to which said jig is fastened having an opening at the front thereof wide enough to accommodate a racket bow head, 115 said jig being fastened to said table at each side of said opening and extending above and over said cut-out portion.

9. Router apparatus comprising a jig shaped to conform to the upper outside portion of a racket bow head and having slots therein, a table to which said jig is fastened having an opening at the front thereof wide enough to accommodate a racket bow head, 120 said jig being fastened to said table at each side of said opening, and means adapted to automatically hold said racket against said 125 jig.

10. A router jig shaped to conform to the upper portion of a racket bow head, 130

guide members on opposite sides of said jig, said jig having a plurality of slots therein extending between and slightly beyond holes drilled in said bow head portion at predetermined points.

11. A router jig shaped to conform to the outer upper portion of a racket bow head, guide members on opposite sides of said jig spaced apart slightly more than the width of said bow head, said jig having slots therein which extend between certain holes in said bow head and slightly beyond.

12. In combination a router and a router jig, said jig being shaped to conform to the outer upper portion of a racket head, guide members on opposite sides of said jig, said jig having slots therein which extend between certain holes in said bow head and slightly beyond, said router embodying a guard adapted to go into and be moved in said slots, and a cutting bit extending beyond said guard.

13. In combination a table and router apparatus, said apparatus comprising a jig shaped to conform to the upper outside portion of a racket bow head having slots therein which extend between and slightly beyond holes drilled in said bow head portion at predetermined points, said jig embodying guide members on opposite sides thereof spaced apart laterally slightly more than the width of said racket bow head, said apparatus also comprising resilient means adapted to hold said racket in working position in said jig between said guide members and a lever to operate said means, said table having an opening at the front thereof wide enough to accommodate said racket bow head, said jig being fastened to said table at each side of said opening and extending above and over said cut-out portion.

14. In working combination, a router and router jig, said jig being shaped to conform to the outer upper portion of a racket head, guide members on opposite sides of said jig between which said racket is adapted to be inserted, said jig having slots therein which extend between certain holes in said bow head and slightly beyond, said router embodying a guard adapted to be inserted into said slots until it touches said racket bow head and adapted to be moved in said slots, and a cutting bit extending beyond said guard into one of said holes a distance equal to the depth of the channel desired to be cut between said holes.

HORACE W. HALL.
